ALFRED G. PLACE, OF YOUNGSTOWN, OHIO; EDNA L. PLACE AND THE DOLLAR SAVINGS AND TRUST COMPANY EXECUTORS OF SAID ALFRED G. PLACE, DECEASED

FEEDING MECHANISM FOR TUBE MILLS

Application filed September 24, 1927. Serial No. 221,710.

There has recently been developed a process for the manufacture of tubes and pipes from a pierced ingot which comprises essentially the rapid intermittent forging of the leading end of the ingot while the latter is supported on a mandrel between a pair of peculiarly grooved rolls rotating in opposite directions and in a direction opposed to the forward movement 10 of the ingot, with the result that each time the ingot is presented to that portion of the rolls grooved to form a pass of predetermined diameter corresponding to the exterior diameter of the tube it is desired to 15 produce, the ingot is reduced in size and brought to the desired exterior diameter so that the tube is progressively formed and gradually projected from the rear side of the rolls until the whole of the metal in the 20 ingot has passed between them. This process is commercially known as the "Pilger" process and the tube mill designed for operation in accordance with the process as a "Pilger" mill.

More specifically, the process contemplates the formation of a cylindrical ingot of somewhat greater diameter than the tube which is to be produced, the axial piercing of the ingot by any suitable means to a 25 diameter approximating that of the internal diameter of the tube and the delivery of the ingot so pierced and while heated, to a proper position in the mill, and in front of the rolls thereof. Upon the attainment of 30 this position by the ingot, a mandrel whose diameter approximates the interior diameter of the tube is then moved longitudinally into the bore or hole in the ingot and the mandrel and ingot then moved forward, preferably as rapidly as possible, until the leading 35 end of the ingot approaches the rolls which latter are rotating in opposite directions and in opposition to the forward movement of the ingot. The rate of longitudinal 40 travel of the ingot is now materially reduced say, under ordinary conditions, to approximately 30" a minute and the leading end of the ingot entered between the rolls while the latter are in such relative position that their 45 respective grooves form an opening suffi-

ciently great for this purpose. As the rolls now continue their rotation those portions of their respective grooves which are formed to the semi-circumference of the exterior of the tube to be formed are brought together 55 upon the end of the ingot with the result that while the ingot as a whole, together with the mandrel, is forced rearwardly, a certain portion of the leading end of the ingot is elongated and reduced in diameter to correspond with the pass between the rolls to thereby form the leading end of the tube. 60 So long as the continued rotation of the rolls maintains the said portions of the roll grooves in juxtaposition, the rearward 65 thrust on the ingot is continued, but the moment that the larger portions of the roll grooves approach each other and thus free the ingot, the mandrel and ingot by suitable means hereinafter described are once more 70 projected forward having meanwhile been given a predetermined axial movement of rotation, so that as the narrower portions of the roll grooves again come into proximity through the rotation of the rolls the 75 latter will again act on the ingot; thus as the ingot throughout the rolling operation is being continuously but slowly moved toward the rolls as above described, a fresh increment of the ingot is presented to the rolls on 80 each forward movement of the ingot with resultant ensuing formation through the action of the rolls of a short section of the tube which latter, as it is thus progressively formed, gradually extends farther and far 85 ther from the rear side of the rolls until all of the metal in the ingot has passed between them and the tube has been completed.

For the carrying out of the several steps incident to the process to which reference 90 has just been made in a very general way, it has heretofore been usual to provide a machine or mill which, essentially, comprises a roll housing in which a pair of rolls respectively provided with grooves formed 95 in accordance with the requirements of the process are mounted one above the other on horizontally extending shafts respectively driven in opposite directions in any suitable way. In front of the rolls is arranged a 100

longitudinally extending pair of horizontal laterally spaced ways, between which and slidably thereupon is disposed a carriage on which is mounted a large air cylinder containing a piston in turn mounted on a rod extending through the ends of the cylinder and axially aligned with the center of the pass between the rolls. At the forward end of this shaft is disposed a coupling head of suitable construction to receive and hold the rear end of the ingot mandrel, while the air cylinder is connected by flexible tubing or in any other suitable way with a large air reservoir located in some convenient position, for example, between the rearmost extremities of the ways. The function of the air cylinder is to provide an air cushion in its rear end against which its piston is forced when the ingot is moved rearwardly through the action of the rolls, the air so compressed behind the piston being effective when the ingot is freed from the grip of the rolls to project the piston, piston rod, mandrel and ingot forwardly in the direction of the rolls so as to present the ingot for engagement by the rolls when their continued rotation again brings the narrow portions of their grooves together to form the pass. Thus, whenever the ingot is in the roll pass it is being forced rearwardly by the operation of the rolls with consequent compression of air in the air cylinder, and whenever it is freed from the grip of the pass it is projected forward for a predetermined distance, limited by the travel of the piston in the cylinder, so as to be received in the pass the next time that the latter is formed, the reciprocation of the ingot being thus effected in timed relation with the movement of the rolls. As hitherto stated, however, in order that each time the pass is formed the ingot may be so disposed as to give the rolls a new bite thereon, the carriage and air cylinder are continuously fed forward during the entire rolling operation from the commencement to the completion of the same, and it has heretofore been usual to employ hydraulic means for effecting this feed as well as for effecting other movements of the carriage during each rolling cycle, that is, the sequence of operations requisite for the production of the tube from the time that the pierced ingot is conveyed to the mill until the tube has been completely formed and the mill placed into position to receive the next ingot. Reference to these additional movements will now be made: When the pierced and heated ingot is brought to the mill the carriage of the latter must necessarily be in retracted position, that is, at least sufficiently far in the rear of the ingot to enable the latter to clear the forward end of the mandrel 65 the rear end of which has previously been,

or is about to be, coupled to its supporting head and, for convenience of operation, the carriage is therefore ordinarily positioned at this time at or near the rear end of its path of travel on the ways. The ingot having been placed between the ways and positioned, generally by means of a suitable elevator, in alignment with the mandrel, the carriage is then moved forward so as to enter the leading end of the mandrel into the rear end of the bore in the ingot and the movement of the carriage then continued till the mandrel has been projected entirely through the ingot and, ordinarily, the rear end of the latter brought into engagement with the face of a grooved collar which has been previously slipped over the mandrel and lies between the rear end of the ingot and the face of the coupling head; this collar is of utility when the mandrel is stripped from the tube as herein-after described. After the mandrel has been inserted in the ingot the forward feed of the carriage is continued until the end of the ingot is brought into proximity to the rolls, and it will therefore be apparent that it is desirable with a view to decreasing the time required for each cycle of operations to effect these several movements of the carriage as rapidly as possible, and thus at a far greater linear speed than that at which the carriage is thereafter moved forward during the actual rolling operation and which, as above stated, ordinarily approximates some 30" a minute, a rate which, under normal conditions of operation, results in a progressive forward movement of the ingot with respect to the rolls of from $\frac{3}{8}$ " to $\frac{5}{8}$ " for each revolution of the latter, the exact amount of this progressive movement, which is of course determined by the rate of continuous linear feet of the carriage, being determined by the size of tubing being rolled, the character of steel employed and other factors well known to those skilled in the art.

Following the completion of the rolling operation and formation of the tube it is necessary to strip the latter from the mandrel which operation is ordinarily performed by positioning a vertically movable dog having a substantially semi-circular notch at its upper end in engagement with the grooved collar on the mandrel to which reference has been made, so as to hold the collar, and in turn the tube, from longitudinal movement and then moving the carriage and mandrel rearwardly for a few inches until the mandrel is loosened from the tube after which it may be withdrawn from the tube rather easily. As the mandrel adheres very tenaciously to the tube a much greater amount of power is required to move the carriage for these few inches necessary to start the mandrel away from

the tube than is required for any of the other movements of the carriage including the subsequent rearward movement thereof required to entirely clear the mandrel from the tube and bring the carriage back to its initial position at the rear of the ways, thereby completing the cycle and placing the mill in condition for the reception of another ingot. Moreover, this short movement at the initiation of the stripping operation requisite for starting the mandrel from the tube must necessarily be performed at relatively slow speed and requires the expenditure of a great amount of power although after the mandrel is once loosened but a relatively small amount of power is thereafter required to complete its withdrawal from the tube. Thus, as in the case when the carriage is moved forward before the rolling operation so as to bring the ingot up to the rolls, it is desirable with a view to economy of time and consequent increase in the productive capacity of the mill to move the carriage rearwardly after the mandrel has started from the tube as rapidly as possible so as to bring it to its initial position in a minimum time.

It is thus apparent that in the carrying out of the process the initial movement of the carriage from the rear of the ways toward the rolls may be made at a relatively high speed; that the subsequent forward speed of the carriage during the rolling operation must be made at a relatively slow speed but accurately, smoothly and continuously, that following completion of the tube a maximum amount of power must be applied to the carriage at the initiation of the stripping operation to move the carriage slowly rearwardly for a few inches only to start the mandrel from the tube and that thereafter the carriage may be caused to complete its rearward movement to initial position relatively rapidly.

As hitherto stated, it has been customary to effect these various movements of the carriage by hydraulically operated means including pistons suitably connected to the carriage and disposed in cylinders extending parallel to the ways in association with means for admitting water under pressure selectively to the opposite ends thereof so as to effect the desired movements of the pistons and in turn of the carriage said means being under the manual control of the operator of the mill. Under practical conditions of operation, however, this method of controlling the movements of the carriage is not entirely satisfactory as it is almost impossible to prevent variations in the pressure of the water supply, pulsations and the like in consequence of which a predetermined opening of the control valves does not always result in the desired or expected movement of the carriage while, additionally, fluctua-

tions frequently occur in its rate of movement. This inability to control the speed and movements of the carriage with the requisite nicety is particularly disadvantageous during the rolling operation for during that portion of the cycle it is substantially imperative that the forward movement of the carriage be continuous, smooth and at a given rate for if this predetermined rate of travel is exceeded, too much of the ingot will be presented to the rolls at each revolution thereof resulting in breakage of the rolls or other parts or stoppage of the mill, while on the other hand, if the predetermined rate is not maintained, difficulty may result from the cooling of the ingot below the proper temperature before the completion of the tube while, in any case, the speed of production is diminished below that of which the mill is capable. Moreover, the use of high pressure water for performing given mechanical operations of the general character to which reference has been made and which are necessarily incident to the use of the Pilger process for producing tubes is always more or less unsatisfactory and a source of annoyance and expense by reason of breakage of pipes and flexible tubing, leakage, difficulties arising in the operation of the pumps and necessity for constant maintenance of an adequate source of water supply.

It is therefore a principal object of the present invention to provide means for effecting the movement or feed of the carriage in a Pilger mill which are not open to the aforesaid objections inherent in the hydraulically actuated mechanism heretofore employed, and more particularly to provide electrically actuated means for this purpose so constructed and arranged that the requisite movements of the carriage may be effected with the nicety, power and speed requisite for satisfactory operation and maximum output of the mill.

Further objects, and novel features and advantages comprehended by my invention will appear more fully hereinafter.

To enable those skilled in the art to readily comprehend and practice my invention I have illustrated in the accompanying drawings and will now proceed to describe certain forms thereof, it being of course understood that by so doing it is not my intention to confine or limit myself to any specific details of construction or arrangement of the various elements as the same are susceptible of material variation from the precise embodiments illustrated and to which reference will hereinafter be made without departing from the spirit and scope of the invention considered in its broader aspects.

In the accompanying drawings Fig. 1 is a somewhat diagrammatic top plan view of a Pilger tube mill embodying one form of

my invention, Fig. 2 is a side elevation thereof and Fig. 3 is a rear end elevation on a somewhat enlarged scale. In both Figs. 1 and 2, it has been necessary, owing to the relatively great size of a mill of this character to break through the figures at several points to enable the same to be placed on the sheet. Fig. 4 is a fragmentary enlarged view, partially in transverse vertical section, indicating in a somewhat diagrammatic way the relative position of the rolls and ingot when a portion of the latter is entering the pass of the rolls and Fig. 5 is a transverse section, partially in elevation, on line 5—5 in Fig. 4, while Fig. 6 is a fragmentary top plan view showing a form of the invention slightly modified from that illustrated in the first three figures. Like symbols are used to indicate the same parts in the several figures.

As the mills of the Pilger type are at present in use and well understood by those familiar with the art, extended description and illustration of the principal parts thereof would be superfluous; therefore the mill proper has been shown in the drawings in a substantially diagrammatic way and will be understood as comprising a roll housing 1 in which are journaled upper and lower rolls 2, 3 arranged to be driven in any suitable manner through the medium of their respective roll shafts 4, 5 in the direction indicated by the arrows in Fig. 4. In front of the rolls and extending rearwardly therefrom are disposed parallel laterally spaced ways 6, 7 on which is slidably disposed a carriage generally designated as 8 and which may comprise front and rear transverse yokes 9, 10 connected by longitudinally extending rods 11. The front yoke 9 forms an integral part of the air cylinder 12 through which extends a piston rod 13 on which within the cylinder is disposed a piston (not shown), the rearwardly projecting end of the rod being surrounded by a guide casing 14. This cylinder may be connected by suitable flexible piping (not shown) with an air reservoir 15 conveniently disposed between the rear ends of the ways and may also serve to support a forwardly extending guide 16 in which is slidably disposed a coupling head 17 mounted on the forward end of the piston rod. To this head is removably secured the rear end of the mandrel 18 through the medium of any suitable coupling device generally designated as 19 while slidably seated on the mandrel is a grooved collar 20 adapted for engagement by the vertically movable dog or stop 21 during the stripping operation.

These several parts are common to mills of this general character and require no further description.

Extending rearwardly from the carriage 8

and conveniently secured at the forward end to the yoke 10 thereof is a long exteriorly threaded rod 25; this rod extends through and is cooperative with a nut or interiorly threaded bore formed in the hub 26' of a gear wheel 26 surrounding the rod and forming part of a gear train having any suitable number of gears to effect the requisite speed reduction hereinafter referred to. This train of gears which, as shown, comprises the gear 26, an idler gear 27 and a drive pinion 28, is disposed in a suitable housing generally designated as 30 arranged transversely of the ways and at a point in the rear thereof so as to be entirely clear of the carriage when the latter is in its retracted or rearmost position the housing, of course, being provided with suitable journals in which the gear shafts are supported. The particular method of mounting and journaling the gears is a matter of choice so long as the parts are arranged in such a way that when the outermost gear constituting the drive pinion of the train, for example, the pinion 28, is driven in a given direction the inner gear 26 will be rotated, conveniently in the same direction, and thus, as the inner gear is restrained from endwise movement by the housing serve to impart to the rod and hence to the carriage a longitudinal movement of 95 in progression the direction of which is determined by the direction of rotation of the pinion. Preferably the outer extremity of the rod may be supported on suitably mounted rollers 32 so as to preserve its proper alignment, the rod of course extending entirely through the gear housing 30.

The drive of the pinion 28 at the outer end of the train is effected from a motor 35 which is coupled by a coupling 36 to the shaft 37 105 on which the pinion is mounted, the motor being conveniently positioned adjacent and in rear of the gear train housing. This motor in accordance with my invention is a direct current motor receiving its power supply from a separate motor-generator set comprising a motor 38 and generator 39 coupled thereto, the several units being so constructed and wound that the direction of rotation of the motor 35 can be controlled by reversing the field of the generator while the speed of operation and power delivered by the motor 35 may be controlled by varying the amount of voltage applied to the generator field. For attaining these several results the motor 35 and generator 39 may be interconnected by wires W through the medium of a suitable control panel P and master switch S. No attempt has been made in the drawings to specifically indicate the requisite wiring between the various units, control panel and the switch as the details thereof form no part of the present invention and are well understood by those familiar with this method of controlling the opera- 130

tion of a direct current motor from a motor-generator set and which is commercially known as the "Ward-Leonard" principle or system of control. Current may be supplied to motor 38 from any suitable source by wires W', while other wires W" may be arranged to supply current to motor 35 for the purpose of exciting its field.

It will thus be apparent that with the various parts arranged substantially as described it is possible by suitable operation of the master switch S to vary the voltage generated by generator 39 and impressed on the armature of motor 35, and also to vary a resistance in series with the field of motor 35 so as to vary the speed thereof and, in turn, the rate at which the gear 26 is turned to thereby move the carriage along the ways in a given direction at a predetermined and constant speed; additionally, by reversal of the field of the generator 39 the direction of rotation of the motor 35 may be reversed so as to move the carriage in the opposite direction. Thus, the operator is able to effect a movement of the carriage along the ways in either forward or reverse direction at relatively high speed as, for example, from 60 to 80 feet a minute by impressing a high voltage upon the motor 35 and is thus enabled to move the carriage from its initial position to carry the ingot I up to the rolls at the commencement of the cycle very rapidly and with a relatively small expenditure of power. Thereafter during the rolling operation the requisite slow forward feed of the carriage approximating, as hitherto stated, some 30 inches a minute, may be readily attained by decreasing the voltage impressed on the motor to a predetermined minimum, and as this voltage is substantially constant and not subject to material variations, the rate of carriage feed during the rolling operation is substantially continuous whereby during each complete revolution of the rolls the carriage, and in turn the ingot, will be moved forward for a predetermined distance so that the same bite will be taken by the rolls on the ingot each time the latter is presented to them.

After the completion of the tube T, by reversing the generator field the requisite reverse movement of the carriage may be as readily effected, at first slowly by the use of a low voltage until the grooved collar 20 is aligned with the dog 21 so the latter can be raised to engage the collar; then by applying a full field to the motor 36 the latter may be caused to exert through the gear train a maximum motor torque and consequent maximum rearward pull on the carriage so as to start the mandrel from the pipe, an operation which requires a carriage movement of some 4" which of course is effected quite slowly owing to the strong adherence of the mandrel to the tube. As soon, however, as

the mandrel is loosened in the tube, the speed of the carriage can be rapidly increased and may thereafter by suitable control of the voltage impressed on the motor, be maintained at any desired rate so as to move the carriage rapidly rearwardly to initial position, desirably, at substantially the same rate at which it was moved forward at the beginning of the cycle.

While for most installations I prefer to employ the threaded rod, nut and gear train for effecting the connection between the carriage and the motor 35, under some conditions it may be preferable, as shown in Fig. 6, to employ a rack 40 instead of the rod, the forward end of the rack being connected to the yoke 10 of the carriage in any suitable way. The teeth with which the rack is provided may be disposed either on its upper or its lower surface; for convenience of illustration they are shown on the former in the said figure. A pinion 41 disposed on a shaft 42 journaled in suitable housings 43 is arranged for cooperation with the rack and the shaft connected, as by a coupling 44, with a gear shaft 45 journaled in a gear train housing 46 disposed adjacent the ways which, however, are not shown in said figure. Upon the shaft 45 may be mounted a gear 47 which forms part of a reduction gear train comprising a suitable number of gears and a drive pinion, for example and as shown, the gear 47, a pinion 48 meshing therewith and disposed on a shaft 49 also carrying a gear 50 engaging the drive pinion 51 on a drive shaft 52 which is coupled, through the medium of a coupling 53, with a motor 35, the ratio of the gears forming the train being of course calculated to effect the desired speed of reduction between the pinion 41 and the motor. The motor-generator set comprising the motor 38 and generator 39 together with the control panel P, master switch S and wiring connections may be the same in this form of the invention as that previously described with resulting similarity of operation.

It will thus be apparent that by the use of my invention the slow, continuous and non-fluctuating forward feed of the carriage and ingot requisite during the rolling operation for the production of the tube with maximum rapidity yet without danger of stopping the mill or damaging the parts thereof may be readily attained; that, with equal facility, a maximum amount of power may be applied to the carriage momentarily to move the latter rearwardly at the commencement of the stripping operation and that whenever desired at other times during the tube-forming cycle, the carriage may be moved rapidly, smoothly and accurately along the ways in either direction with resulting increase in the productive capacity of the mill in a given period.

Moreover, by the use of my invention the difficulties inherent in and annoyances arising from the use of hydraulic means for moving the carriage as heretofore employed in tube mills of the Pilger type are entirely avoided, a mill constructed in accordance with my invention being less liable to get out of order and less subject to shut-downs therefrom than those in which the carriage feed is effected by such means. While therefore the primary object of my invention, as stated, is to enable the carriage to be fed with the requisite nicety and at the maximum speed which can be utilized during the actual rolling portion of the cycle, to at other times enable the carriage to be moved very rapidly along the ways, and to provide means for applying a maximum rearward pull on the carriage when required during the stripping operation, these other advantages arising from the use of my invention to which I have just referred also materially contribute to the practical value of the invention by furthering the productive capacity of the mill and minimizing operating expense over a given period.

Having thus disclosed my invention, I claim and desire to protect by Letters Patent of the United States:

- 30 1. In a machine for forming tubes from a pierced ingot by progressively moving the ingot through a pair of grooved rolls rotating in opposition to the movement of the ingot, a pair of rolls, ways disposed in front of the rolls, a carriage adapted for reciprocation on the ways and means for reciprocating the carriage for feeding the ingot forwardly to the rolls at different speeds and for moving the carriage backwardly at different speeds to produce a slow starting movement and then a rapid backward movement, comprising a motor, means interconnecting the carriage and the motor whereby rotation of the motor in a predetermined direction is operative to impart movement to the carriage in a corresponding predetermined direction, a generator, means for driving the generator, connections between the generator and the motor, and control means operative to vary the output voltage delivered to the motor from the generator whereby said carriage may be moved on the ways at predetermined speeds under different loads by suitably varying said voltage.
- 55 2. In a machine for forming tubes from a pierced ingot by progressively moving the ingot through a pair of grooved rolls rotating in opposition to the movement of the ingot, a pair of rolls, ways disposed in front of the rolls, a carriage adapted for reciprocation on the ways and means for reciprocating the carriage for feeding the ingot forwardly to the rolls at different speeds and for moving the carriage backwardly at different speeds to produce a slow starting

movement and then a rapid backward movement, comprising a motor, means interconnecting the carriage and the motor whereby rotation of the motor in a predetermined direction is operative to impart movement in a correspondingly predetermined direction to the carriage, a generator, means for driving the generator, connections between the generator and the motor and control means operative to vary the output of the generator and polarity and strength of its field whereby said motor may be caused to rotate at varying speeds in either direction so as to correspondingly move the carriage on the ways.

3. In a tube mill of the Pilger type, the combination of a pair of grooved rolls, ways extending from the forward side of the rolls, a carriage slidable on the ways and means for reciprocating the carriage for feeding an ingot forwardly to the rolls at different speeds and for moving the carriage backwardly with a slow starting speed and then a rapid backward movement comprising a motor, means connecting the motor and the carriage whereby rotation of the motor in a predetermined direction will cause movement of the carriage on the ways in a corresponding predetermined direction, a motor-generator set, means for supplying current to the motor thereof, connections between the generator and the first mentioned motor, and control means operable to vary the output of the generator and to effect a reversal of the polarity of its field whereby said first mentioned motor may be caused to rotate at different speeds and in either direction so as to move the carriage on the ways in either direction and at different speeds at different points in its path of travel.

4. In a tube mill of the Pilger type, the combination of a pair of grooved rolls, ways extending from the forward side of the rolls, a carriage slidable on the ways and means for reciprocating the carriage for feeding an ingot forwardly to the rolls at different speeds and for moving the carriage backwardly with a slow starting speed and then a rapid backward movement comprising a motor, a reduction gear train having one end connected with the motor and the other end co-operative with means extending rearwardly from the carriage for moving the carriage in correspondence with the direction of rotation and speed of the motor, a motor-generating set, means for supplying current to the motor thereof, connections between the generator and the first mentioned motor, and control means operative to vary the output of the generator and to effect a reversal of the polarity of its field to thereby control the direction of rotation and speed of the first mentioned motor.

5. In a tube mill of the Pilger type, the combination of a pair of grooved rolls, ways
